UNITED STATES PATENT OFFICE.

CARLTON CLAYTON, OF SYDNEY, NEW SOUTH WALES, AUSTRALIA.

PORTABLE GROUND STANCHION USABLE AS A STRAINER POST.

Application filed March 15, 1928, Serial No. 261,931, and in Australia March 21, 1927.

This invention consists in a novel type of stanchion adapted for setting up on the ground, usable as a post for securing tent lines or suspending hammock beds, and for other 5 like purposes, and usable also as a fence strainer post.

This stanchion consists of a **T** section steel stud adapted to be driven into the ground, with strut feet pivotally hung in a slider 10 which runs on the stud and is clamped to the stud by inward pressure of the strut ends when the struts are extended. A stay is pivotally fixed at one end of it on one of the strut feet with its other end adapted to engage serrations cut in the edge of the web of the stud. The strut feet are foldable back on the stud, thus to minimize space; when so folded two or 15 more complete stanchions may be nested end-for-end and wrapped or rolled within canvas sheet which may be used as a stretcher, mattress, hammock or sunshade, and carried on 20 the running board of a car or otherwise.

The features of a ground stanchion according to the invention are illustrated in the 25 drawings in which:—

Fig. 1 is a perspective view of a complete stanchion in use as a support suspending one end of a hammock bed; it also suggests its use as a strainer post for a wire fence;

Fig. 2 shows the stanchion folded up for 30 packing;

Fig. 3 is a section on the line 3—3, Fig. 1; it shows the preferred section of the strut feet; and

Fig. 4 is a detail perspective view on enlarged scale of the slider; it is explanatory of the punching action of the ends of the strut feet when they are extended at right angles to the stanchion stud.

The stud 10 is in practice always of **T** section; but it might be of **Z**, channel, **L**, cruciform, or other angle section. Its bottom end 11 is sharpened to facilitate driving into the ground. 12 is a strut foot which is in alignment with the web 13 of stud 10, and 14 and 15 are similar strut feet at right angles thereto, aligning respectively with the two flanges of the stud 10. The three strut feet 12, 14 and 15 are constructed of strip sheet folded

to form a **T** section; they are carried by a slider 16 which is most readily built up of a flat back piece and two angles which are united by three rivets or bolts 17 which form pivots for the strut feet 12, 14 and 15 respectively.

When the strut feet are extended to the right angle position as seen in Figs. 1

and 4, their inner ends press into the stud edges and clamp the slider tightly on the stud. The ends of the strut feet which engage the respective edges of the stud are angled off as 60 best shown in Fig. 4 to obtain clearance to permit the folding movement in which they are brought to the nested position shown in Fig. 2. The strut feet are fixed on the ground at their outer ends by staples 22 which are 65 driven into the ground through holes in their flanges.

The web 13 of the stud 10 is drilled with holes 18 for the attachment of fence wires or the like to it and near its top end it is angularly serrated. A stay bar 19 of channel section is pivotally fixed at 20 on the strut foot 12; its top end is engageable with the serrations 21. When set up the stay bar is secured against accidental displacement by a wire loop 23 which is passed through a hole in it and is embraced around the stud 10. This loop hangs on the stud, on which it is slideable, when the assembly is folded for storage or transport as seen in Fig. 2. The stay 19 80 is bent sufficiently to clear the slider 16 in the folded position.

In erecting the stanchion, the stud is first driven into the ground to the desired depth; then the slider 16 carrying the three strut feet 12, 14 and 15 is pushed down until it touches the ground, the strut feet spreading apart till they rest on the ground for their full length. The staples 22 are then driven into the ground to provide a firm anchorage 90 for the strut feet which hold the stud 10 against lateral angular displacement. The slider 16 is securely clamped to the stud by the pinching engagement of the ends of the strut feet with the edges of the stud and any 95 attempt to draw the stud without first removing the staples 22 will only serve to more securely bind the stud in the grip of the slider due to the knuckle action of the ends 24 of the strut feet.

If the stanchion is to be used as a strainer post for fencing wire, the wire ends are looped through the holes 18 as indicated at 30, Fig. 1.

When it is desired to use the stanchion 105 as a support for one end of a canvas bed or the like, end hanger lines are looped through a hole 18 at the desired elevation or a strainer such as 31 may be used. The legs 32 of this strainer are secured midway to a swing bar 33 which is inbound in the end of the canvas sheet 34. The strainer rides upon a cross

pin 35 which is set in a hole 18, and a tensioning screw 40 carries the strainer legs 32 and bears on the back of the flange of the stud 10. 37 are guy wires or cords fastened 5 to the ends of the swing bar 33 and looped through grip loops 38 formed of bent wire which are hung on the ends of the strut feet 14 and 15.

To remove the stanchion, the ground staples 22 are pried up by means of a tool, and the strut feet then tipped up thus to release their clamping grip on the stud. The stud may then be drawn.

The essential feature of the invention is a 15 slider carrying the inner ends of strut feet pivotally, with the ends of the strut feet shaped to engage and bind on the contacting edges of a sectional steel stud when the struts are extended at right angles to the stud.

20 What I claim as my invention and desire to secure by Letters Patent is:—

1. A ground stanchion constituted of a steel stud of angular section adapted to be driven into the ground, a slider adapted for 25 vertical movement along said stud, three

jaws in said slider in 90° relation, ground struts of angle section and pivoted in the respective jaws of the slider with their pivoted ends shaped to engage with and bind on the stud when the struts are spread horizontally 30 and to clear the stud when the struts are in angular relation to the stud, and a stay pivotally fixed at its bottom end to one of said struts and adapted to be engaged at its top end with edge notches in the stud, said stay 35 bent to overlie the slider when the ground struts are collapsed and nested parallel with the stud.

2. A ground stanchion according to claim 1, having the stud and the struts of T section and having drive anchors associated with the struts.

3. A ground stanchion according to claim 1, having the stud and the struts of T section, and the stay of channel section, with a loop 45 hung on the stay to embrace the stud and adapted to hold the stay end in engagement with the notches in the stud.

In testimony whereof I affix my signature.
CARLTON CLAYTON.
